(57) **CLAIM**

I claim the ornamental design for a bow maker, as shown.

DESCRIPTION

FIG. 1 is a front elevation view of the bow maker, showing my new design, the rear elevation view being a mirror image;

FIG. 2 is a left side elevation view thereof;

FIG. 3 is a right side elevation view thereof; and,

FIG. 4 is a top plan view, the bottom plan view being a mirror image thereof.
